TO SAID HERBERT E. BUCKLEN, OF ELKHART, INDIANA

UNLOADER FOR PUMP DRIVES

Application filed September 10, 1926. Serial No. 134,684.

Our invention pertains to automatic unloaders and more particularly to unloader mechanism particularly adapted for use in connection with a reciprocatory member such as that commonly employed to connect a windmill to a water pump. While the unloader is shown as between a wind driven impeller and a water pump it is not to be limited to this use.

10 It is well known that the wind velocity required to start a wind driven impeller from rest is much greater than the velocity required to keep it turning after once the impeller is in motion due to the fact that the area of the impeller's surface is comparatively small and the resultant torque practically nil at zero impeller speed. However, if the propeller is free to start to turn even at a relatively low wind velocity, the torque 15 rapidly increases generally as an exponential function of the R. P. M. That is to say, the impeller of a windmill for driving a pump or the like, has a shunt motor characteristic.

20 Now, since there is relatively little energy in low wind it becomes important to have an impeller the inertia of which may be quickly and easily overcome so that full advantage may be taken of any puffs of wind. 25 It was found that for a given diameter and pitch that a lighter impeller will respond to the winds of low velocity and accelerate faster than a relatively heavy impeller. Therefore, it is highly desirable that the 30 weight be kept at a minimum consistent with strength.

Also, we find that even though the windmill impeller is made as light as practical, still it will not start readily under load. 35 This is especially true when there are only low winds. Furthermore, when the impeller is used to operate a pump, especially those of the deep well type, the resultant load is so great as to prevent the impeller from 40 starting except at relatively high wind velocity.

The principal object of this invention is to provide mechanism for automatically disconnecting the impeller from the load or 45 pump until the impeller is turning at a pre-

determined speed. Obviously, such a disconnecting feature will enable the impeller to start readily even at a very low wind value and to thus enable the operation of the pump down to the last vestige of the wind energy.

55 We are aware that it is common practice to provide automatic unloaders for engines and machines having the so-called shunt motor characteristics. For example, in the case of motor driven compressor units, automatic means is provided for disconnecting the motor from the unit until the motor attains the given speed so as to enable it to start freely. These devices, however, are not suitable for our requirements and we, therefore, propose to provide a novel unloader, particularly adapted for use in connection with well pumps.

60 The device of our invention connects the impeller to the load only when the impeller is revolving at a given R. P. M. Also, if after the connection has been made the wind suddenly drops to a low value, our unloader will 65 respond thereto by decreasing the effective stroke of the plunger rod thus preventing overloading of the impeller during low winds. This arrangement enables the impeller to be responsive to any slight increase 70 in wind value and prevent its complete stopping as long as there is a wind of above approximately two miles per hour.

75 Other objects and advantages of our invention will more fully appear from the following detailed description taken in connection with the accompanying drawings which illustrate several embodiments thereof and in which

Fig. 1 is a vertical sectional view partly in elevation of an unloader built in accordance with the features of our invention;

80 Fig. 2 is an elevation of the unloader shown in Fig. 1 with the exception that a different form of dust shield is employed to cover the moving mechanism;

85 Fig. 3 is an end view taken on substantially the line 3-3 of Fig. 1 looking downwardly;

Fig. 4 is an end view taken from the bottom of the construction shown in Fig. 1 looking upwardly;

90 Fig. 5 is a sectional view taken on the line 130

5—5 of Fig. 1 looking in the direction indicated by the arrows;

Fig. 6 is a fragmentary view partly diagrammatic and partly sectional illustrating our unloader as applied to a wind driven pump;

Fig. 7 is a fragmentary view, partly in section and drawn to an enlarged scale, of the jack or gear mechanism for reciprocating the pump plunger rod; and

Fig. 8 is a diagrammatic view of a modification of our invention.

Referring now to the drawings in detail in which like reference numerals designate similar parts throughout the several views, 10 denotes generally an unloader embodying the features of our invention, (Fig. 6). This device is adapted to be positioned between a windmill construction such as that disclosed 20 in the copending patent application of Herbert E. Bucklen, Serial No. 78,275 filed December 30, 1925, and a conventional water pump. We have designated the wind mill generally by the reference character 11 and the pump by the reference character 12.

The windmill construction 11 as best shown in Fig. 7 includes a two-blade impeller 13 secured to a horizontal driving shaft 14 which extends into a gear casing 15 and is suitably 30 journaled therein. The shaft 14 carries between its ends, a worm 16 which meshes with a wormwheel 17 secured to a shaft 18. The shaft 18 is disposed at right angles to the shaft 14 and is suitably journaled within the casing 15. Fastened to the shaft 18 as disclosed in the copending patent application previously mentioned, is a circular disc or crank member 19 which has fastened thereto an eccentric pin 20. We preferably employ a gear reduction of 12 to 1 as far as the worm 16 and the worm wheel 17 are concerned, so that the plunger makes approximately two strokes to every twenty-four revolutions of the wind wheel or impeller 13.

45 The casing 15 is provided with a lateral extension 21 in which is journaled a pin 22 carrying a rocking arm or lever 23. The shaft 22 has an arm 23' keyed thereto within the casing. This arm is slotted at 24 and receives the crank pin 20, by which the shaft 22 is rocked. The shaft 22 extends to the outside of the casing extension 21 and on said outside end the arm 23 is keyed. The outer end of the arm 23 is provided with a pin connection to the plunger rod 25 of the pump.

The gear casing 15 is fastened to a support member 26 rotatably mounted on top of a tower 27 (Fig. 6). We preferably provide an anti-frictional support for the member 26 by disposing a plurality of anti-frictional balls 28 between the member 26 and the top of the tower 27. The support member 26 is provided with a bore 29 through which the rod 25 extends. Disposed concentric with this bore 29 and secured to the support member

26 is a tube 30 which extends downwardly around the rod 25.

As best shown in Fig. 6 the support member 26 has fastened thereto a pivotable tail vane 31 which does not per se constitute a part of the present invention. The mounting for the tail vane 31 is fully described in the aforesaid copending patent application. Now, the worm wheel 17 is adapted to rotate in the direction indicated by the arrow in Fig. 7 and is at all times in mesh with the worm 16. The crank 19 rotates with the worm wheel 17 and imparts a reciprocatory motion to the rod 25 through the lever 23. Due to the eccentric pin 20 and the slotted leg of the lever 23', a fast down and a slow up movement is imparted to the rod 25. This means that the rod 25 will be moved faster during the idling stroke than during the working stroke. Obviously, this arrangement will result in a much more efficient pump action.

The lower end of the rod 25 is fastened to a yoke or cross head member 32 of the unloader 10. The unloader 10 constitutes a slip connection between the reciprocatory rod 25 and a pump plunger rod 34. The upper end of the plunger rod 34 is secured to a yoke or cross head member 33 of the unloader 10 by means of a set screw 35. The plunger rod 34 extends down through a conventional pump housing 36 having a discharge faucet 37 formed integral therewith. The upper end of the housing has threaded therein a packing gland 38 including a packing nut 39. The housing 36 includes an extension 40 which projects down into the well and connects with a cylinder 41. The lowermost end of the plunger rod 34 is secured to a piston 42 adapted to reciprocate within the cylinder 41 which communicates through an orifice 43 with the water to be pumped. The piston 42 may be of any conventional construction and may include any suitable valve mechanism. The plunger construction shown does not constitute per se a part of our present invention but is illustrated to show the relation between it and our novel unloader. The invention is not limited to the form of pump shown. Any suitable pump may be employed. We shall now proceed to describe in detail the unloader 10.

The yoke or cross head member 32 is connected by a pair of cross rods 45 to a circular flange 46 (Fig. 2). The upper ends of the truss rods 45 are threaded and are secured to the yoke member 32 by means of nuts 47. Similarly the lower ends of the truss rods 45 are fastened to the circular flange 46 by means of nuts 48 threaded thereon. It should be noted that the two truss rods 45 extend through apertures 49 in a circular flange 50 spaced from the flange 46.

The yoke member 33 has secured thereto a pair of parallel truss rods 51 which are fastened at their upper ends to the circular flange 50.

50 by means of nuts 52. The lower ends of the rods 51 are secured to the yoke member 33 by means of nuts 53. The truss rods 51 extend through apertures 54 in the circular flange 46.

5 The rods 45 and 51 alternate in a circular path about the axis of the two flanges 46 and 50. These truss rods are preferably spaced 90 degrees apart. Of course, we desire it understood that although we have only illustrated four of these rods, the invention is not to be limited by this disclosure for any number of them could be employed without deviating from the features of our invention. The flange 46 is formed integral with a circular cylinder 55 which is disposed parallel to the truss rods. This cylinder 55 has a cylinder bore 56 in which a piston 57 is adapted to move. The piston 57 is formed integral with the circular flange 50 and has a circular bore 58. The lowermost part of the bore 56 of the cylinder 55 has a circular shoulder 59 upon which is disposed an annular ring-like washer preferably made of cork. 25 This ring of cork 60 constitutes a cushion or a seat for the lower end of the piston.

The circular flanges 46 and 50 on the cylinder and piston respectively, afford anchorage for the associated truss rods 45 and 51 and 30 also act as guides or supports through which the free rods pass. That is to say, the rods 45 which are secured to the cylinder flange 46 are guided by the piston flange 50 and the rods 51 which are secured to the piston flange 50 are guided by the cylinder flange 46.

35 The rods 45 and 51 are made of such a length that when the assembly is completed the circular boss or extension 61 of the cylinder flange 46 will normally rest on top of the yoke or cross head 32 as is best shown in Fig. 1. Also, it should be noted that the piston flange 50 is provided with a circular boss or extension 62 which is normally spaced from the yoke 32 as indicated at 63 in Fig. 2.

40 As best shown in Fig. 1 it will be observed that the piston 57 fits relatively tight in the bore 56 of the cylinder 55. The hollow piston 57 is provided with a groove 64 preferably annular in shape and located a suitable distance from the extreme lower end of the piston. The location of this groove depends on the length of the cylinder and this factor is to be determined by the maximum stroke required as will become more obvious from the 45 description which hereinafter follows.

The groove 64 communicates with the bore 58 of the piston 57 by means of a plurality of holes 65 drilled on a downward slant, the purpose of which will also be explained later.

50 The cylinder 55 is provided with an annular groove 66 near its upper end and in its interior wall. This groove 66 is adapted to align with the groove 64 in piston 57 when said piston has entered the cylinder a given 55 distance as shown in Fig. 1.

The lower and open end of the hollow piston 57 is threaded internally to receive a valve cage 70 which is threaded externally to fit in the threaded end of the piston as indicated at 71. This cage is provided with a tapered valve seat 72 adapted to have seated thereon a valve 73. Formed integral with the valve 73 is a valve stem 74 which extends through a valve guide 75 formed integral with a bracket 76 (Figs. 1 and 5). The bracket 76 preferably is formed integral with the circular part of the cage 70 threaded into the piston. The guide 75 serves as a bearing for the valve stem 74 threaded at its free end to receive an adjusting nut 77 disposed on top of the bracket 76. The adjusting nut 77 is locked in position on the threaded end of the valve stem 74 by means of a set screw 78 threaded therein. A suitable spring 80 of the compression type is positioned between the valve 73 and the bracket 76 and normally holds valve 73 open a definite degree determined by the adjusting nut 77. That is to say, this spring 80 serves to normally hold the valve 73 off its seat 72. This spring 80 is preferably given just enough tension to insure the opening of the valve at a predetermined low reciprocal movement of the cylinder 55 as will be hereinafter explained. The head of the valve 73 is provided with a 95 small drill hole 79. Instead of a drill hole in the valve head we may use a small slot filed in the valve seat.

Also it should be noted that we have provided the flange 50 of the piston 57 with a 100 small hole 82 having a plug 83 threaded therein through the boss 62. This plug serves to normally close the hole 82 but may be removed to facilitate the loading of the cylinder 55 with oil or for the purpose of replacing 105 oil in the cylinder.

It should be noted that we have positioned between the packing nut 39 and the boss 84 of the cylinder flange 46 a spring 85 preferably of the compression type. This spring surrounds the rod 34 and is adapted to support the weight of the pump rod and piston and hold it in position and at the same time tends to cushion the circular flange 46 on the downward stroke. Also this spring serves to retard excessive downward movement. Figs. 1 and 2 illustrate the full downward position of the rod.

As previously mentioned, we have illustrated in Figs. 1 and 2 two different forms of dust covers for the piston and cylinder. With the exception of the cover, however, both of these views illustrate identically the same device. Fig. 2 is a view showing the unloader of our invention turned 90 degrees with respect to the position of the device as shown in Fig. 1. In Fig. 1 the dust cover or shield 90 comprises a cylinder of flexible material such as cloth, canvas or leather, fastened at its ends to the flanges 50 and 46 of the piston 130

and cylinder respectively. This cover is fastened at each end to the associated flange by means of a wire twisted upon the fabric binding the same into a suitable groove provided in the associated member. The flange 50 has an annular groove 91 for receiving the wire 92 and the flange 46 has an annular groove 93 for receiving the wire 94. (Fig. 1). In Fig. 2 we have illustrated a dust cover comprising a pair of telescoping cylinders 95 and 96. These sleeves or cylinders may be made of any suitable metallic material. A smaller sleeve 95 is secured to the flange 46 by means of screws 97 and the larger sleeve 96 is fastened to the flange 50 by means of screws 98. Either of these two types of dust shields may be employed for covering our novel slip mechanism. It will thus be seen that we have provided a dirt, dust and water-proof housing for both the piston and the cylinder.

The operation of our device is briefly as follows: The unloader is first properly connected to the rod 25 and the plunger rod 34 with the piston and cylinder in telescoping relation. The spring 80 should be properly adjusted by means of the adjusting nut 77 prior to the assembly of the device. Subsequent to the installation of the device in the pumping system, a suitable oil is placed in the cylinder through the filler hole 82 and the cylinder is preferably filled up to the level of the valve bracket 76. We have designated the oil in Fig. 1 by the reference character 100. Of course, we desire it understood that any other suitable incompressible fluid may be used in place of the oil.

Now as soon as a light wind begins to blow having a velocity of about three miles per hour, the impeller starts to turn over very slowly causing the worm 16 and the worm wheel 17 to turn. As previously pointed out, the worm 16 is adapted to turn twelve times as fast as the worm wheel 17. This rotary motion is changed into reciprocatory motion by means of the crank 19 and the lever 23 and is transmitted to the rod 25. The rod 25 causes the yoke or crosshead 33 to lift the cylinder 55 through the means of the truss rods 45. This movement causes the oil in the lower end of the cylinder 55 to flow past the normally opened valve 73 into the hollow piston 57 expelling the air in the piston through the breather hole 81. This upward movement of the cylinder continues slowly until the lower end of the piston has reached the lower end of the cylinder and touches the leather ring or seat 60 or in other words, until the upward stroke is completed. Obviously, if a canvas cover or shield is employed it will have wrinkled up like an accordion during the upward movement and will lie against the truss rod. On the other hand, if telescoping sleeves are employed as a dust shield, the lower sleeve 95 will merely be inserted farther into

the sleeve 96 as is obvious from Fig. 2. During this upward movement the pump rod 34 of necessity would have remained stationary and the distance between the yoke or crosshead 33 and the cylinder flange 46 would equal the maximum upward stroke.

Now upon the downward movement of the rod 25 the cylinder 55 is moved downwardly therewith drawing oil from piston 57 past the valve into the lower section of the cylinder. The oil in the piston is displaced by the air entering the piston bore 58 through the breather hole 81. This downward movement is accomplished at twice the speed of the upward movement due to the eccentric crank pin 20 and the slotted arm 24 of the lever 23. In other words, the rod 25 moves downwardly about twice as fast as it does upwardly. Despite the differential-stroke factor of the pump jack or lever 23, the valve opening is ample to take care of the oil displacement in this stroke without retardation since its size is calculated with this feature in mind.

Upon the conclusion of the downward stroke, the parts will again be in the position shown in Fig. 1. Then too, due to the fact that the impeller is free to start unloaded, its speed has, during this stroke, slightly increased, so that upon the next upward movement of the cylinder the oil is displaced somewhat faster than on the previous movement. This results in an increased rush of oil from the cylinder past the valve in the piston. The return stroke is accomplished in the same manner as previously described. Now when this oil pressure against the valve on the upward stroke is great enough to overcome the tension of the spring 80 and the weight of the valve, it quickly closes, trapping the remaining oil in the cylinder and owing to the incompressibility of the fluid, the rod 25 is enabled to lift the plunger rod 34 to a distance equal to the balance of the upward stroke. That is to say, the trapped oil forms a positive connection between the piston and the cylinder and causes them to move as a unit. Obviously, since the crosshead or yoke 33 is rigidly fastened to the rod 34, the rod 34 must of necessity move with the upwardly moving piston 57.

Moreover, if the space separating the boss 61 of the circular flange 46 and the crosshead or yoke 33 amounts to say two inches at the instant the valve is closed and the total maximum stroke is equivalent to five inches, then the pump rod 34 would be lifted a distance of three inches. On the return stroke of the rod 34 the two inch separation of the parts would be eliminated by the boss 61 again contacting with the yoke 33, and during the remainder of the downward stroke the pump rod and piston would be forced downwardly three inches. As soon as the rod 25 is ready to make its next upward stroke, it will be found that the impeller is rotating at a still

faster speed. This will result in the next upward stroke occurring at a still faster rate causing the valve to close sooner than on the previous stroke and resulting in a less space separating the boss 61 from the yoke 33.

5 This action will continue until the reciprocal speed of the plunger rod 25 is such as to close the valve at practically the very beginning of the stroke, thus resulting in the maximum stroke being applied to the pump rod 34.

10 We preferably adjust the valve 73 to lock at an impeller speed of approximately twenty-four R. P. M. It is evident that since the worm 16 turns twelve times as fast as the worm wheel 17, the rod 25 will make two strokes per minute. We find that this ad-

15 justment will permit actual pumping down to below a three mile per hour wind.

Quite frequently it will be found that the 20 propeller will start up quickly due to a sudden gust of wind and the valve will be closed. A stroke or two will be made and then the wind will die down suddenly leaving the mechanism in the upward position. The

25 spring in the pump rod or the vacuum effect in the pump barrel 41 draws the piston down rapidly enough to hold the valve 73 closed. The weight of the pump rod acting against the worm on the propeller shaft will

30 tend thereby to keep the valve closed so that the unloader does not automatically release. That is to say, the mechanism will be locked on the upward stroke. It will be apparent that the drag or weight of the pump piston

35 and the column of water above it, would pull downwardly on the piston 57 through the rod 34 causing the valve to stay closed thus preventing the impeller from starting from this position in low winds, of say, three or four miles per hour.

40 We meet this condition by providing the small hole 79 in the valve head 73. The release may be provided by cutting a score or groove in the valve seat or the valve face to form the by-pass port. This hole affords a slow release of the oil in the piston bore and hence if the aforementioned condition should occur, the load is gradually released by the leakage of oil past the closed valve. When

45 the oil pressure falls below the valve tension the valve opens thus releasing the load. This will permit pump piston 42 to fully resume its normal downward position until it is supported by spring 85. The main advan-

50 tage of this construction is that it will permit the propeller to again start up without any load being imposed thereon. The size of the by-pass opening 79 in the valve head 73 is just sufficiently large to accomplish its purpose without any appreciable loss of effective strokes at higher stroke speeds.

55 The groove 64 in the piston 57 is adapted to co-operate with the downwardly slanting holes 65 as well as with the groove 66 in the cylinder 55 to collect and salvage any oil leak-

ing past the piston from the lower end of the cylinder when the valve is locked and the oil is under compression. The seepage oil collected by the groove 66 is adapted to flow downwardly through the inclined holes 65 into the bore 58 of the piston 57 on each working stroke. This arrangement prevents loss of oil which would be otherwise forced between the cylinder wall and the piston and out of the top of the cylinder due to the great pressure developed when the device is under load on the working stroke.

60 Obviously, when the reciprocal speed is low enough to permit the cylinder to be completely telescoped by the piston 57, a film of oil will be forced between the wall of the cylinder and the wall of the piston due to the high pressure created in the cylinder. This film of oil will be scraped off of the piston wall by the groove 66 formed in the internal wall of the cylinder 55. This groove 66 will collect the oil when the cylinder is moving downwardly and will discharge the same into the piston through the groove 64 and the drain holes 65, illustrated in Fig. 1. It 65 should also be noted that the piston is provided at its lower end with a series of annular oil grooves 101, preferably three in number, which affords ample lubrication as far as the moving parts are concerned.

65 The previously described combination of grooves and oil holes prevents any loss of oil and at the same time permits ample lubrication of the piston and cylinder walls. The open end of the cylinder 55 is preferably bevelled at 102 as shown in Fig. 1 in order to enable it to shed any moisture which might collect on the upper end of the piston 57.

70 Now we desire it understood that while this device, namely, the unloader 10, is primarily intended for use in connection with an impeller driven pump, that it is equally well applicable to any reciprocal device where the release of the load is desired at some relatively low reciprocal speed and where the 75 clutch action must be practically positive or nonslipping.

75 When operating a pumper, especially a pump of the deep well type, the resultant load is so great as to prevent the impeller from starting except at relatively high wind velocity, but by employing an unloader such as that disclosed and described above, this load can automatically be eliminated temporarily so as to permit the impeller to start readily and easily even though it is subject to a relatively low wind value. Thereafter, our device automatically connects the load to the impeller when the impeller has developed sufficient R. P. M. or torque. The unloader 80 of our invention enables the impeller to handle the load as long as the wind value is above a given point. As soon as the wind value drops or is decreased to a point below the standard set, the load is automatically elimi-

nated permitting the impeller to turn slowly and thus be responsive to any slight increase in wind value and preventing its complete stopping.

From experimentation we found that by using our unloader the impeller started from rest in a four to a five mile wind and began pumping at the second or third stroke, or in other words, the impeller made twenty-four to thirty-six revolutions before the pump was connected thereto by our device. The pump continues to pump water with slightly diminishing strokes down to a wind value of approximately three miles per hour. Below this wind value we found that our device functioned to disconnect the impeller from the load or the pump and thus permitted the impeller to rotate idly very slowly until the wind dropped to below two miles per hour at which value the impeller will gradually come to a stop.

We also have found that with a wind having an average velocity value of approximately three miles per hour we can, by employing the construction disclosed in our present application, pump approximately $67\frac{1}{2}$ gallons per hour. With a wind velocity value of $16\frac{1}{2}$ miles per hour, we found that we could pump with our device 825 gallons per hour; the average stroke being $27\frac{1}{2}$ per minute and the average impeller speed being 330 revolutions per minute. Also we preferably set the wind-mill to turn the propeller out of the wind when this 330 R. P. M. speed is reached.

Without our novel unloader it required an 18 mile per hour wind to start the impeller. The windmill would then continue to pump water down to a four or five mile per hour wind. However, due to the fact that there was no reduction of stroke length at this low wind value, the propeller became rapidly overloaded and consequently stopped. This resulted in no water being pumped until another 18 mile per hour breeze came up.

It will, therefore, be evident that during any continued low wind period when perhaps for days at a time the wind never reaches a velocity above eight to ten miles per hour, the ordinary windmill wheel is incapable of starting due to the magnitude of the load connected thereto. By using our disconnect device or unloader it is possible to not only permit the impeller to turn during these low wind periods but also to pump considerable water. Then, too, the amount of water pumped is greatly increased due to our device automatically decreasing the stroke of the plunger rod during low wind periods, thus preventing the impeller from coming to a complete stop, as long as the wind has a velocity above two miles per hour.

In Fig. 8 we have illustrated diagrammatically a modified form of unloader or clutch. In this construction the impeller driven shaft

125 has secured thereto a rotary pump member 126 having a plurality of reciprocatory vanes or paddles 127. The member 126 is mounted eccentrically in a housing 128 which is suitably connected to the object or load to be turned which, for example, may take the form of a pump drive or like load where the starting torque required is relatively high.

The casing or housing 128 is provided with a U-shaped passageway or by-pass 129 which is connected to the inlet 130 and outlet 131 of the pump. Located in the passageway is a tension valve 132 which may be similar in construction to that located in piston 57 of our preferred form of the invention. This valve is normally open but is adapted to close when the flow of the liquid 133 thereby reaches a given speed.

The operation of this form of our invention is briefly as follows:

Upon the starting of the impeller or other motor, the shaft 125 will rotate relatively slowly. The pump member 126 will rotate with the shaft and pump non-freezing liquid or oil 133 around through the passageway or by-pass 129 since the valve 132 is normally open. As soon as the impeller reaches a given speed, the liquid pressure in the by-pass 129 will be sufficiently great to overcome the tension of valve 132 thus causing it to close. Thereafter the housing 128 and member 126 will rotate as a unit with the shaft 125 thus connecting the load to the impeller shaft 125.

Attention is called to the fact that the sensitive element comprises a valve 73 of relatively large area and small lift providing a relatively large opening for the flow of the oil therethrough on low velocities or differences of pressure. Due to the large area which this valve has, and the small lift required to close it, the device is very sensitive and will close quickly and with but little loss of oil as soon as the proper velocity is reached.

Attention is called to the fact that the inner hollow piston 57 at all times has a very substantial guide in the cylinder 55, so that the tendency to cock or bind is greatly minimized and uneven wear is prevented. At the same time, due to this large guide between the two parts, a tight joint between them may be maintained over long periods of time.

By keeping the level of the oil 100 below the top 102 of the outer cylinder 55, the joint between the piston and cylinder is not subjected to the hydrostatic head, operating at all times to cause leakage, and also it is possible, by keeping the level below the drain hole 65, to permit any excess of oil to be scraped off and returned to the inside of the hollow cylinder 57.

This modification of our invention shows that our invention can be utilized to connect the rotary shaft of the impeller to a load to be rotated as well as to a reciprocatory load.

I have shown the piston as hollow to receive

the oil discharged from the cylinder. Obviously, the invention is not to be limited to this specific construction. I may employ a piston in a double acting cylinder, the oil being driven from the closed end of the cylinder to the end into which the piston rod enters through a by-pass which may be in the piston or in a separate connection as shown for example in the by-pass in Fig. 8.

We desire it understood that our invention is not to be limited by the present disclosure of our preferred modification of the invention, but only in so far as defined by the scope and spirit of the appended claims.

We claim:—

1. In combination, a piston, a cylinder therefor, a valve positioned in the end of the piston within the cylinder, tension means of a predetermined value for normally maintaining the valve open, said cylinder being adapted to contain an incompressible liquid, a flange carried by the free end of the piston, a first crosshead associated with said cylinder flange, truss rods, extending through apertures in said cylinder flange for connecting said crosshead to said piston flange, a second crosshead associated with said piston flange, truss rods extending through apertures in said piston flange for connecting said second crosshead to said cylinder flange and means for causing a relative moving between said piston and said cylinder, said truss rods serving to guide said piston and cylinder.
2. In combination, a tubular piston, a cylinder telescoped by the said piston, valve mechanism associated with the end of the piston inside of the said cylinder, an incompressible liquid carried by the said cylinder, said piston having formed intermediate its ends in its wall a plurality of downwardly slanting holes communicating at their uppermost ends with an annular groove formed in the outer periphery of the piston, said cylinder having an annular groove formed in its inner wall adapted to cooperate with the annular groove of the piston, and means for causing a relative movement between the piston and the cylinder.
3. In combination, a pair of telescoping members, an incompressible liquid in one of said members, and valve mechanism in the other of said members, one of said members having a plurality of inclined holes communicating with an annular groove formed in the periphery of the said member, and the other member having an annular groove formed in its inner periphery adapted to cooperate with the annular groove in said other member, said grooves being adapted to discharge any of the liquid getting between the telescoping walls of the two members back into the inside of the members.
4. In combination, a cylinder, a piston telescoping said cylinder, an incompressible liquid in said cylinder, valve mechanism in said piston adapted to be closed when the liquid attains a given value, and means for causing relative movement between the piston and the cylinder, said cylinder having an annular groove formed in its inner wall adjacent its upper end and said piston having formed in its outer wall an annular groove adapted to cooperate with the said annular groove of the cylinder, said piston also having a plurality of inclined holes communicating with its annular groove, said grooves cooperating to collect any liquid getting between the telescoping walls of said cylinder and piston, and said inclined holes serving to discharge the liquid so collected into the said cylinder.
5. In combination, a cylinder, a piston telescoping said cylinder, an incompressible liquid in the said cylinder, valve mechanism associated with said piston including a valve and tension means, and means for causing relative movement between the cylinder and the piston to cause the liquid in the cylinder to be displaced by the piston, said piston being provided with a bore adapted to receive said displaced liquid, said valve mechanism controlling the displacing of the liquid from the cylinder into the piston, said valve having a small drain aperture permitting the liquid trapped in the cylinder to be returned to the piston.
6. In combination, a pair of telescoping members, each of said members being provided with a flange portion, means for causing a relative movement between said members, an incompressible fluid in one of said members, valve mechanism in the other member, and a collapsible dust cover secured at its ends to said flange portions for enclosing the peripheral portions of said telescoping members.
7. In an unloader, an outer cylinder and an inner hollow piston, said piston having a head comprising a by-pass port, a poppet valve of relatively large area and relatively small lift governing said port, said cylinder being adapted to be filled with liquid to a point below its upper end and to extend up to the piston head.
8. In an unloader, an outer cylinder, an inner hollow piston closely fitting the cylinder, a head member separately connected to the lower end of said piston, said head member having a by-pass port of relatively large area extending therethrough, a conical poppet valve of relatively small lift carried by said head member and governing said port, spring means for holding the valve away from the port, said cylinder being adapted to be filled with liquid up to the head and to a point below its upper end, said piston extending into the cylinder a substantial distance.

distance at all times to provide a relatively long guide between them.

9. In an unloader, a cylinder member, a hollow piston member projecting into the cylinder member and having a head at its end furthest in the cylinder member, a body of liquid disposed wholly within the cylinder, and a check-valved bypass in said head, said check valve having a relatively large diameter and relatively small lift, and a leakage passageway independent of said valve for permitting slow leakage of liquid trapped in the cylinder to relieve the pressure upon the check valve to permit it to open when the parts stand motionless.
10. As a means for connecting a motor with a pump plunger, a pair of plunger rod sections, a cylinder member facing upwardly, a hollow piston member extending down into the cylinder member, said members having bases, cross bars connected to the plunger rod sections, connecting rods connecting the cross bars with the bases, the connecting rods secured to one end being guided in openings in the other base and vice versa, said piston member having a head at its lower end, said head being disposed at all times within the cylinder, and a velocity controlled by-pass in said cylinder head to permit the by-passing of fluid from the cylinder to the interior of the piston below a given velocity of fluid through the by-pass.

11. As a means for connecting a motor with a pump plunger, a pair of plunger rod sections, a cylinder member facing upwardly, a hollow piston member extending down into the cylinder member, said members having bases, cross bars connected to the plunger rod sections, connecting rods connecting the cross bars with the bases, the connecting rods secured to one end being guided in openings in the other base and vice versa, said piston member having a head at its lower end, said head being disposed at all times within the cylinder, and a velocity controlled by-pass in said cylinder head to permit the by-passing of fluid from the cylinder to the interior of the piston below a given velocity of fluid through the by-pass, said velocity controlled by-pass comprising a check valve of large area and small lift, and a body of fluid filling a part only of the cylinder, said head having a by-pass constantly open independently of said check valve to prevent continued locking of the parts together by holding of the valve to its seat when the parts are not in motion.

In witness whereof, we hereunto subscribe our names this 4th day of September, 1926.
